MOTOR CONTROL SYSTEM

Bayard M. Horter, Whitefish Bay, Wis., assignor
to Cutler-Hammer, Inc., Milwaukee, Wis., a
corporation of Delaware

Application March 25, 1935, Serial No. 12,789

6 Claims. (Cl. 242—55)

This invention relates to motor control systems, and more particularly to systems for controlling motor driven machines such as dye jiggers.

5 Machines known as dye jiggers are commonly employed for passing cloth or other material in opposite directions through a bath, such machines being usually provided with a pair of beam rolls either of which is adapted to be driven to wind 10 material thereon as the same is paid out from the other beam roll. The patent to William J. Norton, No. 1,887,462 of November 8, 1932, discloses a dye jigger of the aforementioned type, and proposes use of a pair of shunt wound 15 motors for driving the beam rolls and connections to effect an automatic speed balancing action between the motors to maintain the linear speed of the material and also the tension thereon substantially uniform during transfer of the material from either beam roll to the other. The 20 control system disclosed in said patent also provides for automatic reversal of the motors upon a selected number of revolutions of one of the beam rolls and for plugging of the motors during reversals.

25 The system disclosed in the aforementioned patent for controlling the tension and speed of the material undergoing treatment while having some advantageous features has been found open to serious objections. In practice it has been 30 found necessary to provide modified connections for the motors and it has been found that plugging of the motors during reversals is likely to subject the material undergoing treatment to excessive strains. Also it has been found that 35 reversal of the motors upon a selected number of revolutions of one of the beam rolls is undesirable since the points at which reversals should occur are likely to vary due to shrinkage or stretching of the material during treatment 40 thereof.

The present invention has among its objects to provide an improved dye jigger control system which overcomes the above noted objections to the system of the aforementioned patent.

45 Another object is to provide a dye jigger control system having improved means associated therewith for effecting automatic rocking of the beam rolls.

50 Various other objects and advantages of the invention will hereinafter appear.

The accompanying drawing diagrammatically illustrates an embodiment of the invention which will now be described, it being understood 55 that the embodiment illustrated is susceptible of

modification without departing from the spirit and scope of the appended claims.

In the drawing, Figure 1 diagrammatically illustrates a control system embodying the invention, and

Fig. 2 is a schematic view illustrating an operating mechanism for certain of the control switches shown in Fig. 1.

Referring to the drawing, the same illustrates a pair of direct current dynamo electric machines M^1 and M^2 which are coupled respectively to a pair of beam rolls 1 and 2 for passing material such as cloth through a bath contained in a receptacle 3. The dynamo electric machines M^1 and M^2 are of similar size and construction, each 15 having an armature A and a shunt field winding F to be supplied with current from a direct current supply circuit indicated by lines L^1 — L^2 .

The field windings F^1 and F^2 of the dynamo electric machines are connected in parallel across 20 lines L^1 — L^2 and the armatures A^1 and A^2 of said machines are connected in series and are controlled by an electroresponsive main switch 4, a pair of electroresponsive reversing switches 5 and 6 and a voltage responsive switch 7.

25 Main switch 4 is provided with normally open contacts 4^b for effecting starting and stopping of the equipment, and as hereinafter set forth normally open contacts 5^b and 5^c associated with reversing switch 5 control connections which provide for operation of machine M^1 as a motor and machine M^2 as a generator for winding of the material upon beam roll 1 while normally open contacts 6^b and 6^c associated with reversing switch 6 control connections which provide for 30 operation of machine M^2 as a motor and machine M^1 as a generator for winding of the material upon beam roll 2. Also as hereinafter set forth, upon starting of the equipment in either direction, normally open contacts 7^b associated with switch 7 render the machine which is connected to act as a generator ineffective until the machine which acts as a motor is brought up to a substantially normal speed, and upon stopping of the equipment normally closed contacts 4^c 35 associated with main switch 4 operate to establish dynamic braking connections for the machine which is operating as a generator.

The speed at which the material is transferred from either beam roll to the other and also the 40 tension thereon is controlled by resistances R^1 and R^2 and an adjustable rheostat RH. For a purpose hereinafter set forth rheostat RH is normally shunted by normally closed contacts 1^c 45 associated with the voltage responsive switch 7 50

and resistance R^1 is arranged to be included in the dynamic braking connections established by contacts 4^c of main switch 4.

The energizing circuit for main switch 4 is controlled by a pair of normally open start push buttons 9 and 10 and a plurality of normally closed stop push buttons 11. Also main switch 4 is provided with normally open auxiliary contacts 4^d which act upon response of said switch 10 to establish a maintaining circuit therefor through the medium of the stop push buttons 11.

The start push buttons 9 and 10 also provide for control of the reversing switches 5 and 6 through the medium of an electroresponsive relay 12. Relay 12 is provided with a pivoted contact element 13 which is movable in one direction under the action of an operating winding 14 controlled by push button 9 to bridge a pair of stationary contacts 15-15 and in an opposite direction under the action of an operating winding 16 controlled by push button 10 to bridge a pair of stationary contacts 17-17. Contacts 15-15 of switch 12 control the energizing circuit of reversing switch 5 while contacts 17-17 thereof control the energizing circuit of reversing switch 6. The energizing circuits of reversing switches 5 and 6 are also controlled by normally closed auxiliary contacts 7^d associated with the voltage responsive switch 7 and each of said reversing switches is provided with normally open auxiliary contacts d for establishing a maintaining circuit for itself, and normally closed auxiliary contacts e for controlling the energizing circuit of the other reversing switch. Each of the reversing switches 5 and 6 is also provided with normally open auxiliary contacts f for connecting the operating winding of the voltage responsive switch 7 in shunt with the armatures A^1 and A^2 of the dynamoelectric machines through the medium of a normally closed switch 19 which is operable as hereinafter set forth by the adjusting arm of rheostat RH.

The reversing switches 5 and 6 are also adapted to be automatically controlled by a pair of counting devices 21 and 22, the former device being driven from beam roll 1 and the latter from beam roll 2. Said counting devices are of an indicating type capable of being manually adjusted to provide for zero setting thereof, and counting device 21 is provided with a pair of control switches 23 and 24 while counting device 22 is provided with a pair of control switches 25 and 26. As shown in Fig. 2, the dials of the counting devices each have a notch a on one side thereof which is located opposite the zero figure thereon and the unit dial has a notch b on the opposite side thereof which is shown opposite the numeral 4. Each of the switches 23 and 26 has arms c associated therewith which are arranged to drop into the notches a in the dials of its associated counter when such dials are in zero indicating position and each of the switches 24 and 25 is provided with an arm d which is arranged to drop into the notch b in the unit dial of its associated counter. The switches 23 and 26 are biased to move to closed position, and as is apparent, the arms c associated with said switches prevent closure thereof except upon zero setting of their associated counters. The switches 24 and 25 are also biased to move to closed position and the arm d associated with each of said switches prevents closure thereof except upon movement of the unit dial of its associated counter into a given indicating position, as for example 4. As hereinafter set forth, the switches 23 and 26 are arranged to be con-

nected in circuit with the operating windings of relay 12 by the manually controlled switches 27 and 28 to effect automatic reversal of the dye jigger upon paying out of all of the material upon either of the beam rolls 1 or 2. Also as hereinafter set forth the switches 24 and 25 are adapted to be connected in circuit with the operating windings of relay 12 by manually controlled switches 29 and 30 to automatically rock the beam rolls upon winding of all of the material 10 upon either of said beam rolls.

The function and operation of the aforescribed control system and also the circuit connections thereof will now be more fully described.

Depression of either of the start push buttons 9 or 10 establishes an energizing circuit for main switch 4 extending from line L^1 through the stop push buttons 11 through push button 9 or 10, as the case may be, to conductor 32 and thence through the operating winding 4^a of said main switch to line L^2 . In responding main switch 4 establishes a maintaining circuit for itself extending from line L^1 through stop push buttons 11 to conductor 33 and thence through the auxiliary contacts 4^d of said main switch and the operating winding 4^a thereof to line L^2 .

Depression of start push button 9 connects the operating winding 14 of relay 12 across lines L^1-L^2 through the medium of the stop push buttons 11 and said relay is then moved into position to establish an energizing circuit for reversing switch 5 extending from line L^1 through contacts 7^d of voltage responsive switch 7, through contacts 6^e of reversing switch 6 to and through the operating winding 5^a of reversing switch 5 and through contacts 15-15 of relay 12 to line L^2 . Reversing switch 5 then responds and establishes a maintaining circuit for itself extending from line L^1 through its auxiliary contacts 5^d and through its operating winding to line L^2 as already traced. Upon response of main switch 4 and reversing switch 5 the armature A^1 of machine M^1 is energized by a circuit extending from line L^1 through contacts 5^b of reversing switch 5, through said armature to conductor 34, through resistances R^1 and R^2 and through contacts 7^c of the voltage responsive switch 7 and contacts 4^b of main switch 4 to line L^2 . Machine M^1 then operates as a motor to effect paying out of material from beam roll 2 and winding thereof upon beam roll 1.

Depression of start push button 10 connects the operating winding 16 of relay 12 across lines L^1-L^2 through the medium of the stop push buttons 11 and said relay is then moved into position to establish an energizing circuit for reversing switch 6 extending from line L^1 , through contacts 7^d of voltage responsive switch 7, through contacts 5^e of reversing switch 5, to and through the operating winding 6^a of reversing switch 6 and through contacts 17-17 of relay 12 to line L^2 . Reversing switch 6 in responding establishes a maintaining circuit for itself extending from line L^1 through its auxiliary contacts 6^d and through its operating winding 6^a to line L^2 as already traced. Upon response of main switch 4 and reversing switch 6 the armature A^2 of machine M^2 is energized by a circuit extending from line L^1 , through contacts 6^c of reversing switch 6, through said armature to conductor 34, through resistances R^1 , R^2 , and through contacts 7^c of the voltage responsive switch 7 and contacts 4^b of main switch 4 to line L^2 . The dynamo electric machine M^2 then operates as a motor to effect paying out of ma- 75

terial from beam roll 1 and winding thereof upon beam roll 2.

When either of the reversing switches 5 or 6 responds the contacts *f* thereof connect the operating winding 7^a of voltage responsive switch 7 in shunt with the armatures A¹, A² through the medium of switch 19. Thus when either of the machines M¹ or M² is started as a motor the other machine acts as a generator to supply winding 7^a with current the voltage of which is a function of the speed of the former machine. Upon response of reversing switch 5 machine M¹ acts as a motor, as hereinbefore set forth, and when said machine is brought up to a predetermined speed switch 7 responds and armature A² is then connected across resistances R¹, R² and rheostat RH by contacts 7^b of switch 7 and contacts 5^c of reversing switch 5. Machine M² then operates as a braking generator and to effect tensioning of the material during winding thereof upon beam roll 1. Upon response of reversing switch 6 machine M² acts as a motor as hereinbefore set forth, and when said machine is brought up to a predetermined speed, switch 7 responds and armature A¹ is then connected across resistances R¹, R² and rheostat RH by contacts 7^b of switch 7 and contacts 6^b of reversing switch 6. Machine M¹ then operates as a braking generator to effect tensioning of the material during winding thereof upon beam roll 2.

In practice it has been found that when either of the machines M¹ or M² operates as a motor and the other machine as a braking generator an automatic speed balancing action between the machines is obtained which provides for transfer of the material at a substantially uniform speed and a substantially constant tension.

In connection with the foregoing it should be noted that when either of the machines is started as a motor the rheostat RH is shunted by contacts 7^c of the voltage responsive switch 7 to insure quick acceleration thereof. However, upon response of switch 7 the contacts 7^c open to include rheostat RH in the armature circuits of both machines and said rheostat is then effective to regulate the tension on the material undergoing treatment. As is apparent, movement of the arm 35 of rheostat RH towards the right includes resistance and thus decreases the braking effect of the machine acting as a generator to thereby decrease the tension on the material undergoing treatment, while movement of said arm towards the left has an opposite effect.

It should also be noted in connection with the foregoing that when relay 12 is operated to reverse the direction of operation of the equipment the reversing switch which is closed at the time of reversal and also the voltage responsive relay 7 must drop out before an energizing circuit for the other reversing switch can be established. Thus during reversals, the machine associated with the beam roll upon which the material is to be wound is always brought up to a predetermined speed before the machine associated with the other beam roll is brought into action as a braking generator.

As hereinbefore stated, the auxiliary contacts *f* of reversing switches 5 and 6 provide for energization of the voltage responsive switch 7 through the medium of a normally closed switch 19 associated with the rheostat RH. Switch 19 is adapted to be opened by a cam associated with the adjusting arm 35 of rheostat RH to prevent response of switch 7 when said arm is adjusted 75 to include sufficient resistance to prevent oper-

ation of the machine associated with the unwinding roll as a braking generator. Thus when all of the material is wound upon either of the beam rolls, switch 19 may be opened to render the machine associated with said beam roll ineffective as a braking generator during winding of the material upon the other beam roll.

Depression of either of the stop push buttons 11 effects interruption of the aforescribed maintaining circuit for the operating winding of main switch 4. Main switch 4 then drops out to interrupt the energizing circuit for the machine which is operating as a motor and the contacts 4^c thereof establish a dynamic braking circuit for the machine which is operating as a braking generator. Assuming that the equipment is stopped with a reversing switch 5 in closed position contacts 4^c establish a dynamic braking circuit for the machine M² extending from the left hand terminal of armature A² through resistance R¹, through contacts 4^c of main switch 4 and through contacts 5^c of reversing switch 5 to the right hand terminal of armature A². On the other hand, assuming that the equipment is stopped with reversing switch 6 in closed position contacts 4^c establish a dynamic braking circuit for machine M¹ extending from the right hand terminal of the armature A¹, through resistance R¹ through contacts 4^c and through contacts 6^b of reversing switch 6 to the left hand terminal of armature A¹. Thus provision is made for effecting stopping of the equipment by dynamic braking of the machine associated with the unwinding beam roll.

As hereinbefore stated, the counting devices 21 and 22 provide for automatic reversal of the equipment upon paying out of all of the material on either of the beam rolls, and the function and operation of these devices will now be more fully described.

Assuming that the material is to be transferred to beam roll 1 from an untreated roll mounted upon beam roll 2. Prior to winding of any of the material upon beam roll 1 counter 21 is set at zero and the equipment is then set in operation by push button 9 to effect winding of the material upon said beam roll. When all of the material is paid out from beam roll 2 the equipment is stopped by depression of one of the stop push buttons 11. The operator then sets counter 22 at zero, closes switches 27 and 28 and starts the equipment in a direction to effect winding of the material upon beam roll 2 by depression of start push button 10.

Upon paying out of all of the material upon beam roll 1 counter 21 returns to zero and switch 23 closes to establish an energizing circuit for winding 14 of relay 12 extending from line L¹ through the stop push buttons 11 by conductor 33, through contacts 4^d of main switch 4, by conductor 32, through switch 27, and through switch 23 and the operating winding 14 of relay 12 to line L². Upon energization of winding 14 relay 12 operates to effect energization of reversing switch 5 and the equipment is thus automatically reversed to effect winding of the material upon beam roll 1. Upon paying out of all of the material upon beam roll 2 counter 22 returns to zero and switch 26 closes to establish an energizing circuit for winding 16 of relay 12 extending from line L¹ through the stop push buttons 11, by conductor 33, through contacts 4^d of main switch 4, by conductor 32 through switch 28 and through switch 26 and winding 16 to line L². Relay 12 then operates to effect energization 75

of reversing switch 6 and the equipment is thus automatically reversed to effect winding of the material upon beam roll 2. The counters 21 and 22 thus provide for automatic reversal of the equipment each time all of the material upon either of the beam rolls is paid out. It should be noted that when the counters are set as hereinbefore described the same will always return to zero upon paying out of all of the material associated with their respective beam rolls, regardless of stretching or shrinkage of the material during treatment thereof.

It is necessary to provide for rocking of the beam rolls when all of the material is wound upon either of the same to prevent settling of the dye or liquor on the underside of the roll, and as will now be set forth the switches 29 and 30 control this operation. When all of the material on beam roll 2 is paid out and wound upon beam roll 1 the switch 26 associated with counter 22 operates as hereinbefore set forth to reverse the direction of operation of the equipment to effect rewinding of the material upon beam roll 2. With switch 29 in closed position, switch 25 acts upon a given angular movement of beam roll 2, as for example four revolutions thereof, to establish an energizing circuit for winding 14 extending from line L¹ through the stop push buttons 11, by conductor 33, through contacts 4^d of main switch 4, by conductor 32, through switches 27, 29 and 25, and through the operating winding 14 to line L². Relay 12 then operates to energize reversing switch 5 for rewinding of the material upon beam roll 1, and upon four revolutions of beam roll 2 the switch 26 again closes to effect reversal of the equipment. When all of the material on beam roll 1 is paid out and wound upon beam roll 2 the switch 23 operates as hereinbefore described to reverse the direction of operation of the equipment to effect rewinding of the material upon beam roll 1. With switch 30 in closed position, switch 24 acts upon a given angular movement of beam roll 1, as for example four revolutions thereof, to establish an energizing circuit for winding 16 extending from line L¹, through the stop push buttons 11, by conductor 33, through contacts 4^d of main switch 4, through switches 28, 30 and 24 to and through the operating winding 16 to line L². Relay 12 then operates to energize reversing switch 6 for rewinding of the material upon beam roll 2 and upon four revolutions of beam roll 1 the switch 24 again closes to effect reversal of the equipment. Thus provision is made for rocking either of the beam rolls upon winding of all of the material thereon, and as is apparent, rocking operations can be discontinued at any time by opening the switch 29 or 30, as the case may be.

60 What I claim as new and desire to secure by Letters Patent is:

1. A control system comprising, in combination, a pair of direct current dynamo electric machines for transferring material from either of two rolls to the other, each of said machines having a shunt field winding, means for selectively establishing power connections for the armatures of said machines to effect starting of either of said machines as a motor and to thereafter render the other of said machines operable as a braking generator, an armature regulating resistance common to said machines and means associated with said former means for shunting said regulating resistance during starting of either of said machines as a motor.

2. A control system comprising, in combination, a pair of direct current dynamo electric machines for transferring material from either of two rolls to the other, each of said machines having a shunt field winding, means for selectively establishing power connections for the armatures of said machines to effect starting of either of said machines as a motor and to thereafter render the other of said machines operable as a braking generator, a regulating resistance common to said machines and means associated with said former means for preventing operation of either of said machines as a braking generator upon inclusion of a given amount of said regulating resistance.

3. A control system comprising, in combination, a pair of direct current dynamo electric machines for transferring material from either of two rolls to the other, each of said machines having a shunt field winding, an armature resistance common to said machines, means for selectively establishing power connections for the armatures of said machines including said resistance to render either of said machines operable as a motor and the other of said machines as a braking generator, means associated with said former means for preventing operation of either of said machines as a braking generator until the same is brought up to a predetermined speed and means associated with said last mentioned means for excluding a portion of said armature resistance during starting of either of said machines as a motor.

4. A control system comprising, in combination, a pair of direct current dynamo electric machines for transferring material from either of two rolls to the other, each of said machines having a shunt field winding, common armature resistance for said machines including a regulating rheostat, means for selectively establishing power connections for the armatures of said machines including said resistance to render either of said machines operable as a motor and the other of said machines as a braking generator, said means including an electromagnetic switch responsive to complete the armature circuit for said last mentioned machine upon a given speed thereof, and means for interrupting the energizing circuit for said switch upon given settings of said rheostat.

5. A control system comprising, in combination, a pair of direct current dynamo electric machines for transferring material from either of two rolls to the other, each of said machines having a shunt field winding, common armature resistance for said machines including a regulating rheostat, means for selectively establishing power connections for the armatures of said machines including said resistance to render either of said machines operable as a motor and the other of said machines as a braking generator, said means including an electromagnetic switch responsive to complete the armature circuit for said last mentioned machine upon a given speed thereof, means associated with said switch for normally shunting said regulating rheostat and means for interrupting the energizing circuit of said switch upon given settings of said rheostat.

6. In a system for transferring material from either of two beam rolls to the other, in combination, a dynamo electric machine coupled to each of said beam rolls, means for reversibly operating said machines as a motor and as a generator, and as a generator and a motor, respectively, a device associated with each of said beam rolls for counting the number of revolutions thereof, each of said counting devices being manually adjustable to provide for zero setting thereof upon paying

out of all of the material from its associated beam roll, means associated with said counting devices and acting upon zero setting thereof to control said reversing means for operation of either of said machines as a motor upon paying out of all of the material from its associated beam roll and means also associated with said

counting devices and operable upon rewinding of a relatively small amount of material upon either of said beam rolls to control said reversing means to effect operation of the machine associated with the other beam roll as a motor. 5

BAYARD M. HORTER.
